UNITED STATES PATENT OFFICE.

OSCAR MUSSINAN, JR., OF NEW YORK, ASSIGNOR TO EBERHARD FABER, OF WEST NEW BRITTON, NEW YORK.

DESIGN FOR A PEN-HOLDER.

SPECIFICATION forming part of Design No. 21,195, dated December 1, 1891.

Application filed March 26, 1891. Serial No. 386,565. Term of patent 7 years.

To all whom it may concern:

Be it known that I, OSCAR MUSSINAN, JR., a citizen of the United States, residing in the city and State of New York, have invented a new Design for a Pen-Holder, of which the following is a full, clear, and exact description.

The leading feature of this design for a pen-holder consists in spirally-fluted ornaments extending along the handle, with a tapering plain portion at the upper end of the handle and with a plain cylindrical portion at the pen end of the holder, the spiral flutings tapering down to and vanishing in the tapering plain portion.

In the drawing the design is represented by a side view. The general configuration is round and tapering and the surface is fluted spirally, as represented at *a*, the smaller end of the holder being a plain taper, as at *b*, and the pen end of the handle is plain.

I claim—

The design for a pen-holder, substantially as herein shown and described.

Signed by me this 24th day of March, 1891.

O. MUSSINAN, JR.
